CHARLES THOMAS BATTLE

INVENTOR
by J.H. Weatherford
ATTORNEY.

UNITED STATES PATENT OFFICE.

CHARLES THOMAS BATTLE, OF MEMPHIS, TENNESSEE.

SHIELD FOR HANGERS.

Application filed November 2, 1925. Serial No. 66,166.

This invention has general reference to shields adapted for use with hangers and other devices for suspending various objects, but relates particularly to such shields which are intended to be applied to garment hangers.

The principal objects of the present invention are to provide a shield that,

(a) Preferably is made by a cutting operation, from a blank of semi-rigid and somewhat resilient material, which is initially flat, and may readily be formed by hand into shape for use in the intended manner;

(b) Is readily attachable to and detachable from a suspension member of skeleton construction, or otherwise so formed as to present a limited suspension surface, no implement being required for such attachment or detachment;

(c) Is of unitary construction;

(d) Has no abrasive surfaces or exposed, sharp projections, and no metal parts; and

(e) Affords clear spaces upon which advertising matter or the like may be inscribed.

The means by which the foregoing and other objects are accomplished by my invention, and the manner of their accomplishment, readily will be understood from the following description on reference to the accompanying drawings, in which,—

Fig. 1 is a perspective view of a well-known form of garment hanger, having my improved shield applied thereto.

Fig. 2 is a plan view of the blank from which the shield is formed.

Fig. 3 is a section on line III—III of Fig. 1.

Fig. 4 is a plan view of a portion of a blank, showing an alternate form of the securing tongue.

The hanger 5, shown in Fig. 1 for purposes of illustration, is of a form that is commonly used for suspending garments which it is desired to protect from wrinkling or otherwise getting out of shape. Hangers of this sort are usually made from a single piece of wire, which is bent mechanically to form a suspension hook 6, two similar inclined suspension portions 7, and a straight suspension portion 8. As ordinarily used for hanging men's garments, the coat and waistcoat are suspended from the inclined portions 7, and the trousers are draped over the straight portion 8. Owing to the very limited surface area of the wire

from which the hanger is made, it has a tendency to form undesirable creases in the parts of the garments with which it is in contact, and this is especially true as regards trousers or other garments that are hung over the straight portion 8.

My improved shield preferably is formed from a rectangular blank 9, of relatively stiff cardboard or the like, which is cut, by hand, in a press, or by any other preferred mechanism, to form two similar V shaped or U shaped, tongues 10, and two similar slits 11, said parts being in such positions and of such sizes and shapes that the slits are adapted for the insertion of the free ends of the respective tongues therein. The alternate form of tongue 10^A, shown in Fig. 4, is provided with shoulders 12, to assist in retaining the tongue in place after its insertion into the slits 11.

The blanks are intended to be packed, shipped and stored in a flat condition, and not to be bent into shield form until they have been or are about to be applied to the hangers.

Each blank is then folded preferably without creasing, along approximately its longitudinal center line, and owing to the semi-rigidity and the resiliency of the material from which the blank is made, it

will retain substantially the cross-sectional configuration shown in Fig. 3, with its two legs 13 and 14 diverging.

The shield thus formed is secured in place over the suspension member in connection with which it is to be used, such as the straight portion 8 of the hanger 5 by inserting the ends of the tongues 10 or 10^A, in the slits 11, or 11^A, and bending them down, as indicated at the right-hand side of Fig. 1.

If the tongues 95 are of the form shown in Fig. 3, they should be inserted in the slits 11^A past the shoulders 12, so that said shoulders will assist in retaining the tongues in place.

While I have shown my improved shield 100 as being applied to the straight portion 8, only of the hanger 5, it is manifest that similar shields may if desired be applied to the inclined portions 7. Also, it should be noted that use of this form of shield is not 105 confined to any specific type of hangers, or to the suspension of any particular article or articles, but that it has a wide range of application, such for example, as being placed over a clothes line or a clothes rack. 110

While the blanks are in a flat condition, advertising or other matter may be in-

scribed upon one or both of the leg portions 13 and 14, and since such portions retain substantially plane surfaces after the blank is bent into shield form, such inscriptions 5 will be plainly visible.

Various modifications of my improved shield will doubtless suggest themselves to those skilled in the art to which it appertains, and I therefore do not desire to be 10 limited to the exact details of the invention as shown in the accompanying drawings, and described herein. For example, the blank may be of other than rectangular shape, or the shapes or locations of the 15 tongues or of the slits may be varied, without departing from the intended scope of my invention.

Having now fully described my invention, what is claimed is:—

- 20 1. A device of the character described, comprising a strip of semirigid, resilient material having an opening therein, and a tongue, formed by cuts extending outward toward and intersecting an edge of said strip, cooperable with said opening for retaining said strip in place upon a suspension member.
- 25 2. A device of the character described, comprising a strip of semirigid resilient material having a plurality of slits therein, and tongues, each formed by converging cuts extending outward towards and intersecting an edge of said strip, cooperable with said slits for retaining said strip in place upon 35 a suspension member.
- 30 3. A device of the character described, comprising a strip of material having a plurality of slits each extending longitudinally thereof, and tongues at opposite sides of said 35 strip, each formed by cuts extending outward toward and intersecting a different edge of the strip, co-operable with said slits
- 40

for retaining said strip in place upon a suspension member.

4. A device of the character described, 45 comprising a strip of semirigid, resilient material having a slit therein, and a tongue formed by cuts extending to an edge of said strip, and intersecting said edge at the same point, said tongue being adapted to cooperate with said slit for retaining said strip upon a suspension member.

5. A device of the character described, comprising a strip of material having an 55 opening therein, a tongue formed by cuts extending outward toward and intersecting an edge of said strip, and adapted for entry into said opening to retain said strip in place upon a suspension member, and means for opposing removal of said tongue from 60 said opening.

6. A shield for a suspension member, comprising a strip of resilient material adapted to be bent manually to substantially V-shape to fit over said member, said strip having 65 slits therein, and tongues cooperable with said slits for retaining said strip in place upon said member while retaining said shape.

7. A shield for a hanger, comprising an initially flat strip of semirigid resilient material adapted to be bent manually over said hanger, leaving the portions of said strip at the opposite sides of the hanger diverging from each other at a considerable angle, 75 said strip having slits therein, and tongues each narrower at its free end than at other parts thereof, adapted to cooperate with said slits for retaining said strip in place upon said hanger while retaining said angular divergence.

In testimony whereof I have hereunto set my name.

CHARLES THOMAS BATTLE.
